UNITED STATES PATENT OFFICE.

OLIVER HEGGLUND, OF OAKLAND, NEBRASKA.

RABBET-PLANE.

SPECIFICATION forming part of Letters Patent No. 274,600, dated March 27, 1883.

Application filed December 5, 1882. (No model.)

To all whom it may concern:

Be it known that I, OLIVER HEGGLUND, of 5
Oakland, in the county of Burt and State of
Nebraska, have invented a new and useful Im-
provememt in Rabbet-Planes, of which the fol-
lowing is a full, clear, and exact description.

This invention consists of a contrivance of
the handle of a rabbet-plane for adjusting it
into several different positions with relation
10 to the plane, to adapt the plane for holding in
different ways for different kinds of work, as
hereinafter described.

Reference is to be had to the accompanying
drawings, forming a part of this specification,
15 in which similar letters of reference indicate
corresponding parts in all the figures.

Figure 1 is a side elevation of a rabbet-plane
with a handle applied according to my inven-
tion. Fig. 2 is an end elevation. Fig. 3 is a
20 section of figures on line $x-x$; and Fig. 4 is a
perspective view of the nut employed, together
with the binding-screw for securing the handle.

A represents the plane-stock, on the back
end of which I attach the block B by screws
25 a , so that it can be readily detached, said block
having a recess, C, between ears D, wherein
I pivot the handle E, as shown, on the binding-
screw F, on which screw the handle can
30 turn when not screwed up tight by the screw,
the said screw being fitted in the ears D, and
traversing the recess C, on which the handle
is located, and screwing into a nut, H, in one
of the ears in which said nut is fitted so as not
35 to turn, so that it can draw up against the
handle and bind it fast against the other ear.

K is a set-screw screwing into the recess from

the back of the block and binding against the
nut of the handle to secure it in any position
in which it may be set. The handle is con-
structed with the bend L, for the purpose of 40
enabling it to be turned over the back of the
block B, as shown by the dotted lines in Fig.
2. The block B is detachably connected to
the plane-stock, as before stated, for the pur-
pose of detaching it and attaching a long 45
straight handle projecting rearward of the
plane-stock, and in line with it, when the plane
is to be used for dressing deep mortises.

Having thus described my invention, I claim
as new and desire to secure by Letters Patent— 50

1. In a rabbet or other plane, the combina-
tion, with the recessed block or support se-
cured upon the rear end of the stock, of the
pivoted handle having the bend L, the pivotal
screw, and the holding or adjusting screw, sub- 55
stantially as and for the purpose set forth.

2. In a rabbet or other plane, the combina-
tion, with the recessed block or support se-
cured upon the rear end of the stock, of the
handle having its hub arranged in the recess
of said block, against which hub bears a hold-
ing or set screw, the pivotal screw, and binding-
nut, fitted to slide in one of the ears of the
block and to bear against one end of the han-
dle-hub, and adapted to be operated by the 65
pivotal screw, substantially as and for the pur-
pose set forth.

OLIVER HEGGLUND.
